FIG. 1.

FIG. 2.

Mayo S. Haselton INVENTOR.

UNITED STATES PATENT OFFICE.

MARJORIE S. HASELTON, OF WASHINGTON, DISTRICT OF COLUMBIA.

DESIGN FOR A BODY OF VEHICLE-LAMPS.

57,974.

Specification for Design.

Patented May 24, 1921.

Application filed September 30, 1920. Serial No. 413,924. Term of patent 7 years.

To all whom it may concern:

Be it known that I, MARJORIE S. HASELTON, a citizen of the United States, residing in the city of Washington, District of Columbia, have invented a new, original, and ornamental Design for a Body of Vehicle-Lamps, of which the following is a specification, reference being had to the accompanying drawing, forming a part thereof.

Figure 1 is a side elevation of the body of a vehicle lamp which is my new design.

Fig. 2 is a front elevation of my new design.

I claim—

The ornamental design for a body of vehicle lamps as shown or its equivalent.

MARJORIE S. HASELTON.
